2 Claims. (Cl. 250—20)

The invention comprises devices for the reception of frequency modulated waves. It is known that with those waves not the amplitude but the frequency varies rhythmically in accordance with modulating potentials. The amplitude of frequency modulation is dependent on the particular signal strength.

For receiving it is necessary to convert the frequency modulated waves correctly into variations of amplitude. Formerly one has used special converters. Such a converter can be, for example, an inductivity having a linear frequency characteristic as long as one keeps sufficiently beneath or above the resonance frequency.

One object of the invention is a superheterodyne receiving device working without a converter for changing frequency modulation into amplitude modulation.

Another object of the invention is keeping exactly the frequency at a constant value, for example, the intermediate frequency appearing in superheterodyne receivers.

A still further object of the invention is the linear amplification of frequency modulated waves.

The invention is especially useful for ultra short wave devices of a wave length of less than 1 metre but it is not limited to those wave lengths.

The fundamental feature of the receiving device is the variation of the local oscillator in regard to its frequency in such way that a constant intermediate frequency is the result. The variations of frequency in regard to the calculated value are to be used as a control quantity. The control quantity is retroactive upon the oscillator in such manner, that the intermediate frequency is kept as exactly as possible at its calculated value. The control quantity varies rhythmically with the frequency modulation of the received waves and can be made audible in a telephone or the like. Thus a special converter is not necessary because the control quantity itself shows exactly the variations of amplitude according to the variations of frequency. For this purpose a linear relation between the variations of frequency in dependence on the regulation value must exist, and this condition is easy to fulfill. Furthermore the limiting device for the amplitude is not necessary.

Carrying out such a regulation one can use as the control quantity the variation of frequency itself. An exact calculation shows that such a regulation indeed is possible. For this

purpose one needs a frequency bridge device which produces the control quantity. In this case there must be a remaining deviation of the calculated value which is dependent on the control steepness so that an exact controlling to deviation zero is not possible (static regulation). Since this condition may exist at image frequencies the regulation is active in the reverse sense as there are no negative frequencies. Hence, it is necessary that the apparatus employed actually diminish the deviation.

According to a preferred embodiment of the invention these disadvantages can be avoided by adjusting the oscillator in another way. For this purpose a quantity is used being proportional to the phase difference between the intermediate frequency and a constant auxiliary oscillator. This desired result is obtained from the phase relations which exist in an oscillatory circuit. The latter is tuned to the intermediate frequency ω_0 of the carrier wave. If the frequency of the received wave varies the phase relations between current and voltage in the oscillatory circuit vary too and the oscillatory circuit is highly sensitive for such variations.

The objects of the invention will be understood best from the following specification in connection with the drawings in which:

Fig. 1 shows the principle circuit of the receiver,

Fig. 2 is a graphical representation of the frequency relations,

Fig. 3 shows the phase bridge device and

Figs. 4a and 4b show the vector diagram of the bridge device,

Fig. 5 shows a modification of the phase bridge device of Fig. 3.

Figs. 6 and 7 represent characteristics curves of the mode of operation of the receiver,

Figs. 8 and 9 show in principle the regulation of the oscillator tube,

Fig. 10 is a graphical representation of the frequency-variations,

Fig. 11 shows the diagram of connections of an amplifier and

Figs. 12 and 13 show the mode of operation of the amplifier.

The principle of the invention is schematically represented in Fig. 1. The received frequency modulated vibrations are superheterodyned with the vibrations of a local oscillator. The resulting intermediate frequency is indicated in Fig. 1 with B and it is to be kept at a constant value as far as possible. Furthermore the auxiliary transmitter A is provided having an exact

constant standard frequency. The frequencies a and b produced by both the transmitters A and B come together on a phase bridge device P_h and the produced control quantity u is retroactive to the intermediate frequency B in such manner that its frequency is varied about ω and coincides with a frequency a (see also Fig. 2). As this regulation of the phase bridge device is taking place only in respect to the phase there is the advantage that the regulation down to the deviation zero is possible as the control quantity does not become smaller with decreasing difference of frequency. Furthermore the above described difficulties in regard to the image frequencies fall off, as there exist of course no negative frequencies but a negative phase. The coordination of the control quantity to the phase difference therefore has but one meaning.

The regulation regarding this occurs as follows: Both frequencies a and b being different at the beginning let it be known that they possess a gradually increasing phase difference ϕ . This permanently increasing phase difference produces in the phase bridge device a control quantity being retroactive to the intermediate frequency b in such way that the phase difference is diminished. The frequency b will be adjusted regarding its phase to frequency a . In the final state of the regulation a fixed phase difference is reached being just large enough to keep the control quantity u to a constant value. Contrary to the above described regulation in the final state no deviation from the calculated value of frequency is necessary. In the state of equilibrium both frequencies have exactly the same value and differ only by a constant phase difference (astatic regulation).

For this reason the phase shifting at the oscillatory circuit between current and voltage is to be transformed into corresponding direct currents. The principal diagram of connections of such a phase converter is shown in Fig. 3. With T_1 and T_2 two transformers are shown being fed by the voltages U_1 and U_2 . The secondary winding of transformer T_1 is connected with the anodes of a duo-diode D whilst the secondary winding of T_2 is connected to the cathode of the diode D and to the middle tap of secondary winding of transformer T_1 . The ratio of the two transformers T_1 and T_2 is proportional to 2:1. If the two voltages U_1 and U_2 have a phase difference of, for example, 90° one gets the vector diagram according to Fig. 4a. The angle of phase ϕ is 90°. The voltages U_a and U_n along the spaces between cathode and anodes of the duo-diode have the same amplitude. The corresponding currents J_0 and J_n have therefore also the same value. If the phase ϕ has not the value of 90° other relations result as shown, for example, in Fig. 4b. The voltage along both spaces of the duo-diode now are different and therefore are causing different currents. In the case $U_1=2$ and $U_2=1$ the voltage at the duo-diode are:

$$U_0 = 2 \sin \frac{\phi}{2}$$

and

$$U_n = 2 \cos \frac{\phi}{2}$$

The value calculated by these formulae have but one meaning between 0° and 180°. As at an oscillatory circuit larger phase displacements do not occur the regulation has but one meaning.

For converting the currents again into voltages

being more favorable for purpose of regulation it is advantageous to change the circuit according to Fig. 3, as shown by Fig. 5. The corresponding numbers of signs are the same as in Fig. 3. The transformer T_1 is divided into two parts T_1' and T_1'' and is on its secondary winding short circuited by the condensers C_1 and C_2 for the high frequency. The currents J_0 and J_n are flowing through two resistances R_0 and R_n and thus the control voltages at these resistances are gained.

The voltage U_1 , for example, may be produced by transmitter A (standard frequency) whilst the voltage U_2 will be produced by the intermediate frequency transmitter. The differences of phases between both voltages produce in the duo-diode the voltages U_a and U_n as is shown in Fig. 4. The control quantity can be gained at the points P and Q (Fig. 5) and is proportional to the currents J_0 and J_n . The characteristic curve of the diode can be assumed linear and therefore one gets for the control quantity:

$$u = K_1 \cos \phi$$

Now it is assumed that the standard oscillator A vibrates with the constant frequency a . It is now the question in which manner the regulation of the intermediate frequency b is dependent on time. For the oscillations of the transmitter A and B one gets (see Fig. 2):

$$Y_1 = \sin at$$

$$Y_2 = \sin [at - \int_0^t (D - \omega) dt + \rho_0]$$

It is remarkable that ω is not constant but a function of time t itself.

The difference of phase between these two oscillations is:

$$\phi = \int_0^t (D - \omega) dt + \rho_0$$

ϕ_0 being the difference of phase at the beginning. In substituting this value into the equation for the control quantity one gets:

$$u = K_1 \cos [\int_0^t (D - \omega) dt + \rho_0]$$

It is always possible that the regulation of frequency of oscillator B by the control quantity u is linear. One thus can write:

$$\omega = K_2 \cdot u$$

In substituting into this equation the value of the control quantity u one gets the equation for ω :

$$\omega = k \cos \left[\int_0^t (D - \omega) dt + \rho_0 \right]$$

where $K = K_1 \cdot K_2$, which also may be called as resulting steepness. This equation leads to a differential equation, which becomes finally:

$$t = \int_0^t \frac{dz}{D - K \cos z} + C'$$

where

$$\cos z = \frac{\omega}{K}$$

In the special case of $D = K$ the equation is:

$$t = \frac{1}{D_0} \int_0^t \frac{dz}{1 - \cos z} + C'$$

The solution of this equation is:

$$z = \arccos \frac{(Dt + C)^2 - 1}{(Dt + C)^2 + 1}$$

The starting conditions being $t=0$ and $\omega = D \cdot \cos \phi_0$, one gets the constant C :

$$C = \frac{1 + \cos \rho_0}{1 - \cos \rho_0}$$

The relations as above are shown in Figs. 6 and

7. The constant C is ∞ at $\rho_0=0$, it has the value 1 at $\rho_0=90^\circ$ and the value 0 at $\rho_0=180^\circ$. In Fig. 7 the quantity ω is shown in dependence on time t and quantity C and at the same time the term $x=Dt+C$ is chosen. The asymptotical course of the curve shows that at all values of ρ_0 a correct adjustment of transmitter B takes place. In other words this means that the receiver is properly controlled for all differences of phases in the starting point. Starting oscillations are decreasing quickly, oscillations of regulations do not occur. If especially in the beginning both the vibrations have the phase difference zero against each other the oscillator B will be at once oscillating in the correct frequency.

In Fig. 8 a principal diagram of connections of the receiver according to the invention is shown. The oscillations coming from the antenna will be superposed with the vibrations of the oscillator O. In the duo-diode an intermediate frequency will be produced being signed B. This intermediate frequency will be given to one branch of the phase bridge device Ph and before this eventually will be amplified in the amplifier RV, which now can be a resonance amplifier, for there takes place a regulation of oscillator O in such manner that a constant intermediate frequency results. The standard oscillator A leads its constant frequency to the other branch of the phase bridge device. The control voltage produced in the bridge device is retroactive to the oscillator O and makes the adjustment of the latter. Besides this the current for the telephone or the like is gained from the control quantity and there might also be provided between 35 same a low frequency amplifier NF. In this embodiment the oscillator is a brake field generator and the control quantity gained in the bridge device Ph acts on the voltage of the brake field electrode. The negative voltage of the brake field electrode is given by battery Q.

The shown phase bridge device corresponds to that of Fig. 5. The windings of the transformer being circuited into the anode leads of the duo-diode are connected through resistances and condensers in parallel-connection for reaching a favorable receiving of the diode voltages.

Fig. 9 shows a complete embodiment of the invention in which a brake field tube is controlled. The voltage which is to be controlled in respect to its frequency is led at 1 to an amplifier comprising the shield grid tube 2. The amplified voltage runs to the oscillatory circuit 5 which transforms the variations of frequency into phase shiftings. After further amplification in transformer T_0 and tube 3 the voltage is led to transformer T_2 corresponding to transformer T_2 in Fig. 5. One part of the controllable voltage 1 will be divided before or behind the first amplifier tube 2, for example, at 5 and will be led to transformer T_1 , being subdivided into two parts T_1' and T_1'' as shown in Fig. 5 and which secondary winding is connected with the anodes of the duo-diode D. These two parts of windings are short circuited for high frequency by the condensers C_1 and C_2 . The control voltage will be tapped at the resistance R_0 and R_n , for example, in such manner that the brake field electrode of tube 7 is connected with point 4. The battery for the brake field electrode is signed e. The anode voltage for the amplifier tubes 2 and 3 is connected at +A.

If the voltage 1 has its calculated value in respect to the frequency no difference of phase results at the oscillatory circuit 5. The difference 75

of the device is therefore zero. If on the contrary the frequency voltages in the phase bridge of voltage 1 varies, phase differences at the oscillatory circuit will appear in regard to the voltage tapped at 5 and the hereby caused voltages in the bridge device effect variations of the brake field voltage of tube 7. The latter serves as oscillator and effects the adjusting of frequency of the intermediate frequency produced in the diode

10 8.

The advantages of the invention are such that several parts of the superheterodyne receiver especially the limiting device and the converter can be left off. As a result of this one reaches an essential simplification of the receiver, for example, in respect to a diminution of the number of tubes. Thus one gets a lesser disposition for disturbances as well as a smaller consumption of energy, a smaller weight and smaller costs of the device. The greatest advantage is that the sensitivity of the receiver i. e. the range of reception will be enlarged. This is caused by using a resonance amplifier through which passes only a small band of frequency. By this the noise is lowered for the latter is proportional to the root of the width of band of frequency.

In regard to the amplifying of frequency modulated waves certain considerations are necessary.

It is well known that at the amplifying of amplitude modulated waves nonlinear distortions exist being caused by the curved course of the characteristics of the tubes. Besides the course of phase between current and voltage in dependence of the frequency is less essential. For frequency modulated waves the conditions are contrary. In this case the nonlinearity of the characteristics of the tubes lose their importance however the course of phase produces linear and nonlinear distortions.

The following description will show by calculation the bad influence of the course of phase and finally an arrangement is shown which will avoid or diminish the distortions in aperiodic amplifiers.

With frequency modulated waves the frequency varies according to the rhythm of modulation. The carrier or middle frequency is signed ω_0 and the variation of frequency is ω_m . The latter is dependent on the time $\omega_m(t)$, i. e. periodically according to the modulation frequency Ω . At the input of the amplifier the frequency is ω_e (momentary frequency). That is:

$$\omega_e = \omega_0 + \omega_m(t)$$

In Fig. 10 the frequency ω is drawn as ordinate against the time t as abscissa. The frequency ω varies to both sides about the value ω_0 .

It may be assumed that the waves may be modulated sinusoidally with the modulating frequency Ω . Then the oscillation can be expressed by the following equation:

$$y_e = A \cdot \sin [\omega_0 t - b \cos \Omega t] = A \cdot \sin [\varphi_e(t)]$$

From this one gets the frequency in differentiating the phase $\varphi_e(t)$ in respect to the time t :

$$e = \frac{dy_e}{dt} = \omega_0 + b \cdot \Omega \cdot \sin \Omega t = \omega_0 + \omega_m(t)$$

where $\omega_m(t) = b \cdot \Omega \cdot \sin \Omega t$. The quantity $b \cdot \Omega$ is called amplitude of frequency (see Fig. 10).

In the amplifier now phase displacements are existing being dependent on the momentary value of ω_e . The oscillation at the output of the amplifier is:

$$y_a = A \cdot \sin [\omega_0 t - b \cos \Omega t + \alpha(\omega_e)] \\ = A \cdot \sin [\varphi_a(t)]$$

In this case $\alpha(\omega_e)$ is the phase displacement being dependent on the frequency. In regard to the frequency behind the amplifier follows that

$$\begin{aligned}\omega_a &= \frac{d\omega_a}{dt} = \omega_0 + b \cdot \Omega \sin \Omega t + \frac{d\alpha}{dt} \\ &= \omega_0 + b \cdot \Omega \sin \Omega t + \frac{d\alpha}{d\omega_e} \frac{d\omega_e}{dt}\end{aligned}$$

The term

$$\frac{d\omega_e}{dt}$$

means now:

$$\frac{d\omega_e}{dt} = b\Omega^2 \cos \Omega t$$

In substituting this value in ω_a one gets:

$$\omega_a = \omega_0 + b\Omega \sin \Omega t + \frac{d\alpha}{d\omega_e} b\Omega^2 \cos \Omega t$$

$$\omega_a = \omega_0 + b \cdot \Omega \cdot [\sin \Omega t + \frac{d\alpha}{d\omega_e} \Omega \cos \Omega t]$$

Whilst now the frequency modulation before the amplifier is:

$$\omega_m(t) = b \cdot \Omega \cdot \sin \Omega t$$

behind the amplifier it is as follows:

$$\omega_m'(t) = b \cdot \Omega \left[\sin \Omega t + \Omega \frac{d\alpha}{d\omega_e} \cos \Omega t \right]$$

If

$$\frac{d\alpha}{d\omega_e}$$

const., one can transform the term in parentheses in known manner and it is received the following equation:

$$\omega_m'(t) = b \cdot \Omega t + \sqrt{2 \frac{d\alpha^2}{d\omega_e}} \cdot \sin(\Omega t + B)$$

In this case only variations of the amplitude take place effecting a lifting of the higher frequencies according to the term

$$\sqrt{1 + \Omega^2 \frac{d\alpha^2}{d\omega_e}}$$

Therefore only linear distortions occur.

In general the term

$$\frac{d\alpha}{d\omega_e}$$

is however a function of time for it is possible to develop ω_e into a Fourier-series. Therefore it is:

$$\omega_m(t) = b \cdot \Omega [\sin \Omega t + \Omega \cos \Omega t + \{c_0 + c_1 \cdot \cos \Omega t + \dots\}]$$

Thus here are acting the products of sin and cos members i. e. $\omega_m(t)$ is nonlinear distorted and therefore also at the converter, which transforms the frequency modulations into amplitude variations, nonlinear distortions are received.

For avoiding these distortions the amplifier can be constructed of several single parts shown in Fig. 11. Each part contains a tube I having between anode and cathode the unavoidable capacity C. Furthermore the inductance L and the ohmic resistance R is connected in series connection between anode and cathode tube I. The input of the amplifier is named E and the output A. To A one or more other amplifiers are connected. Now it is the question whether the quantities R, L, C can be chosen in such way that the demanded reception without any distortion can be reached.

The conductivity of the anode circuit is:

$$G = \frac{1}{R} = j\omega C + \frac{1}{R+j\omega L} = \frac{1}{R} \cdot \frac{1 + \omega C L}{1 + j\omega R L}$$

(where j is the root of -1).

For simplifying the calculation the following abbreviations may be chosen:

$$RC = T, \omega RC = \omega T = x, \frac{L}{R^2 C} = k$$

From there follows:

$$\frac{\omega L}{R} = kx$$

and

$$\omega^2 LC = k \cdot x^2$$

With these abbreviations one can write:

$$20 \quad GR = \frac{jx + 1k \cdot x^2}{1 + j \cdot k \cdot x}$$

$$= \frac{1}{1 + (k \cdot x)^2} + j \frac{k^2 x^3 + (1 - k) x}{1 + (k \cdot x)^2}$$

25 From this follows for the phase angle α

$$\operatorname{tg} \alpha = k^2 x^3 + (1 - k) x$$

In the following the two cases may be considered:

30 $k=0$ and $k=1$, i. e. $L=0$ and $L=R^2 C$.

1. $k=0$

$$\alpha = \operatorname{arc} \operatorname{tg} x$$

$$\frac{d\alpha}{dx} = \frac{1}{1 + x^2}$$

2. $k=1$

$$\delta = \operatorname{arc} \operatorname{tg} x^3$$

$$\frac{d\alpha}{dx} = \frac{3x^2}{1 + x^6}$$

These curves are shown in Fig. 12. From there it is to be seen that in both curves the course of phase is in counterclockwise. It is therefore to be expected that in series connection of two such amplifiers a course of phase results having lesser phase variations than each single amplifier. For abbreviation the following terms are chosen:

$$z = \frac{d\alpha}{d\omega} = \frac{d\alpha}{dx} \frac{dx}{d\omega}$$

As is shown above it is:

$$x = \omega T$$

therefore

$$\frac{dx}{d\omega} = T$$

60 From this follows:

$$z = T \frac{d\alpha}{dx}$$

For reaching a good compensation of the series connection a displacement of the scale is necessary. For $k=0$ the abscissa is $x=\alpha$ and for $k=1$ the abscissa is $x=T$.

1. $k=0$:

$$z_0 = T_0 \frac{d\alpha}{d\epsilon} = T_0 \frac{1}{1 + \epsilon^2}$$

2. $k=1$:

$$z_1 = T_1 \frac{d\alpha}{d\epsilon} = T_1 \frac{3r^2}{1 + r^6}$$

The displacement of the scale may be given by the constant in the following manner:

$$\epsilon = \tau \cdot r$$

The value of the constant τ shall be given by the condition that at the intersection of both curves ($r=\xi, \epsilon=\kappa \cdot \xi$) the ordinate $z_0=z_1=\xi$ is half the value of z_0 at the point $\epsilon=0$. In this case the value of the resultant curve at the intersection point will be the same as the beginning where the value of curve 2 (corresponding to $k=1$) is zero, as is shown in Fig. 12. In this case it is expected that the resultant deviation differs only little from these values. The mathematical expressions are:

$$z_0(\tau, \xi) = z_1(\xi) = \frac{1}{2} z_0(0)$$

i. e.

$$T_0 \frac{1}{1 + (\tau \xi)^2} = \frac{T_0 3\xi^2}{1 + \xi^6} = \frac{1}{2} T_0$$

(for

$$z_0(0) = T_0 \frac{1}{1 + 0}$$

As shown above:

$$\epsilon = T_0 \cdot \omega$$

$$r = T_1 \cdot \omega$$

$$\frac{\epsilon}{r} = \frac{T_0}{T_1} = \tau$$

Therefore:

$$\tau \frac{1}{1 + (\tau \xi)^2} = \frac{3\xi^2}{1 + \xi^6} = \frac{1}{2}$$

$$\frac{1}{1 + (\tau \xi)^2} = \frac{1}{2}$$

$$\frac{1}{1 + (\tau \xi)^2} = \frac{3\xi^2}{1 + \xi^6}$$

From these equations one can gain τ and ξ . The result is:

$$\tau = \frac{1}{\xi}$$

$$\xi = 0.56$$

$$\tau = 1.79$$

The equation for the resulting curve for the series connection is:

$$z = z_0 + z_1 = T_0 \frac{3x^2}{1 + x^6} + T_1 \frac{1}{1 + (\tau x)^2} = \frac{dx}{d\omega}$$

In Fig. 13 this curve is signed with number 3. In practice one uses the range between $x=0$ and $x=0.56$. The variations are very small.

The last equation expresses: for getting no variations in the course of phase

$$\frac{dx}{d\omega}$$

up to a distinctly limiting frequency ω_g in the range $x=0$ to $x=0.56$, two amplifiers with the predetermined tube capacities C_0 and C_1 have to be connected in series. The first amplifier has only the resistance R_0 for $L_0=0$ as $k=0$. The second amplifier has the series connection of the resistance R_1 and the inductivity

$$L_1 = R_1^2 C_1 \text{ as } k=1$$

The quantities T_0 and T_1 are connected to each other over the constant $\tau=1.79$. It is $T_0=\tau \cdot T_1$. 75

In considering $T_0=R_0 C_0$ one gets the three equations:

$$\omega_g C_0 R_0 = 0.56$$

$$1.79 C_1 R_1 = C_0 R_0$$

$$L_1 = R_1^2 C_1$$

In these three equations except the predetermined quantities ω_g , C_0 and C_1 the unknown quantities R_0 , R_1 and L_1 are stated which can be determined in a manner having but one meaning.

What I claim is:

1. In a heterodyne type receiver for receiving ultra high frequency modulated signals, a circuit for receiving said signals, a local oscillator connected to said circuit for producing an intermediate frequency in conjunction with said frequency modulated signals, a fixed reference oscillator, control means comprising a phase bridge and voltage regulating means connected between the phase bridge and said local oscillator for regulating said local oscillator to maintain said intermediate frequency substantially constant, said phase bridge comprising, a double diode having cathode means and two anodes, and two transformer means each of which has a primary winding and a secondary winding, one of said transformer means having its primary winding connected to said fixed reference oscillator and having its secondary winding divided into two equal sections with the opposite ends of the secondary winding connected respectively to the two anodes of said double diode, the other of said transformers having its primary winding connected to said signal receiving circuit to receive the intermediate frequency and having its secondary winding connected between said cathode means and the juncture of the two sections of the secondary winding of the first-named transformer, and audio frequency responsive means connected to said voltage regulating means.

2. In a heterodyne receiver for receiving ultra high frequency modulated signals, a double diode having two anodes and cathode means to cooperate with the two anodes, means connecting each of the anodes with the cathode means, a circuit for receiving said signals, a local oscillator connected to said circuit for producing an intermediate frequency in conjunction with said frequency modulated signals, transformer means having a primary winding connected to said circuit to receive said intermediate frequency and a secondary winding in said connecting means with one terminal connected directly to said cathode means whereby the signal is impressed in series with said cathode means, a fixed reference oscillator, a divided transformer means having primary winding means connected to said fixed reference oscillator and having two equal secondary winding portions connected together in said connecting means and respectively associated with said two anodes with each anode connected directly to one terminal of the secondary winding portion associated therewith, the juncture between said secondary winding portions being connected to the first-named secondary winding on the side opposite said cathode means, whereby said double diode and said transformer means form a phase bridge, a second circuit connected between said phase bridge and said local oscillator for regulating the latter to maintain said intermediate frequency substantially constant, and audio frequency responsive means connected to said second circuit.
